UNITED STATES PATENT OFFICE.

SIDNEY A. REEVE, OF WORCESTER, MASSACHUSETTS, ASSIGNOR TO CHARLES F. BROWN, TRUSTEE, OF READING, MASSACHUSETTS.

COMPRESSOR-VALVE.

SPECIFICATION forming part of Letters Patent No. 755,317, dated March 22, 1904.

Application filed March 21, 1901. Serial No. 52,143. (No model.)

To all whom it may concern:

Be it known that I, SIDNEY A. REEVE, of Worcester, in the county of Worcester and State of Massachusetts, have invented certain new and useful Improvements in Compressor-Valves, of which the following is a specification.

This invention relates to gridiron-valves controlling the admission or discharge of an elastic-fluid compressor; and it has for its object to combine certain advantages of both automatic or self-acting valves and positively-operated valves.

With this end in view the invention consists in devices hereinafter described and claimed for combining a positive closing of the valve with an automatic or self-timed opening, for obtaining an ample and quick opening, and for minimizing friction of entrance and exit of air.

Of the accompanying drawings, forming a part of this specification, Figure 1 represents a longitudinal sectional view of a compressor provided with admission and discharge valves constructed in accordance with my invention, the section being taken in a plane which shows the admission-valves and their operating mechanism. Fig. 2 represents a section on the line 2 2 of Fig. 1 on a larger scale. Fig. 3 represents a longitudinal section of one end of the cylinder, taken in a plane which shows the discharge-valve. Fig. 4 represents a transverse section showing a modified form of discharge-valve.

The same reference characters indicate the same parts in all of the figures.

Referring to the drawings, 1 represents a compressor-cylinder, having a piston 2, actuated from a crank-shaft 3. Outside of the cylinder-head 4 at each end is an inlet-chamber 23 and a discharge-chamber 18. Each cylinder-head is provided with a set of gridiron admission-ports 5, controlled by a gridiron slide-valve 6, mounted upon the inner side of the cylinder-head and having a valve-stem 7, at the outer end of which is secured a piston 8, operating in a dash-pot cylinder 9. The said dash-pot cylinders 9 are connected by links 10 with wrist plates or levers 11, 11,

pivoted to fixed supports, and said wrist-plates 50 are connected by links 12 with a three-armed lever 13, oscillated by an eccentric 15 on the crank-shaft 3 through an eccentric-rod 14. In each dash-pot the cylinder-space above the piston 8 is provided with a vent-outlet 16, 55 whose orifice is controlled by a vent-valve 17, and between the piston 8 and the lower head of the dash-pot cylinder is interposed a spring 170.

The operation of the admission-valves is as follows: The wrist-plates 11 tend to impart such reciprocating movements to the valves 6 as would fully open each valve as the piston starts to recede from that end of the cylinder and fully close said valve when the piston has reached the opposite end of the cylinder and a cylinder full of elastic fluid has been admitted through the ports 5. At the beginning of the admission-stroke, however, just before the piston starts to recede and re-expand the clearance fluid remaining in the cylinder from the previous compression-stroke this clearance fluid creates an excess of pressure within the cylinder over that external thereto, which excess or differential pressure 75 acting on the inner side of the valve 6 tends to hold said valve to its seat by friction and prevent its opening after the wrist-plate 11 has started on its valve-opening movement. The wrist-plate starts on its valve-opening 80 movement at or just before the moment when the piston 2 reaches its dead-point. The dash-pot cylinder 9 therefore starts to move upwardly, while the piston 8 remains substantially stationary, and the spring 170 is 85 thereby put under compression, which increases as the movement of the wrist-plate continues. As the piston recedes, however, the pressures on opposite sides of valve 6 approach a balance, and the static friction between the valve and its seat decreases until a point is reached at which the tension of the spring 170 overcomes such friction and causes the valve to open. A sudden and full opening of the valve then occurs, and the inertia 95 acquired by the valve under the influence of spring 170 is overcome by the compression created by the dash-pot piston 8, which com-

pression may be regulated by varying the orifice of the vent 16. When the time comes for closing the valve 6, the friction due to unequal pressures on the valve is absent, and 5 there is a positive timing of its closing movement effected by an actual meeting of the piston 8 with the upper head of the dash-pot cylinder or by a slight air-cushion between the two.

10 In the case of the discharge-valves 24 24 the valves are located on the outside of the cylinder-heads within the discharge-chambers 18. The valve mechanism for operating these valves is not shown in full, being a duplicate 15 of that for operating the admission-valves 6, with the exception that the eccentric is so located as to tend to open each valve at or after the beginning of a compression-stroke and close it at the end of said stroke. At the beginning 20 of the compression-stroke when the valve is closed the pressure in chamber 18, being greatly in excess of the pressure within cylinder 1, holds the valve 24 by friction in close position against its seat. The outward 25 movement of the dash-pot cylinder 9 under the influence of the wrist-plate begins at such a time as to be well under way by the time the compression in cylinder 1 equals the pressure of the exhaust-chamber 18, which is that 30 of the system which the compressor supplies. The valve therefore receives a quick and ample opening, which is automatically timed, according to the degree of compression which exists. Its closing movement is positively 35 timed and may occur with more or less air-cushion in the dash-pot.

The principal advantages of my gear are—

First, automatic timing for the valve's opening, with positive timing for its closing.

40 Second, rapidity of opening, due to the accumulation of motive forces previous to the instant when the valve starts into motion. It is plain that the longer the opening is delayed, as would be the case with discharge-valves 45 working against a heavy head-pressure, the more rapid will be the opening, because of the increased previous accumulation of motive force. In this respect the gear is an improvement over both positively-moved and automatic discharge-valves, for the former, 50 whether operated by eccentric, cam, or other similar means, finds its maximum possible velocity lessening as the time of opening in the stroke becomes later, and the latter, although 55 opening more sharply and quickly under the conditions stated, is apt to have its accuracy of closing impaired by this delayed accentuated opening.

Third, amplitude of opening. In this respect 60 all positively-moved valves are superior to automatics; but my invention is superior to other positively-moved valves in that with them the maximum opening of the valve must occur at or about half-way between opening 65 and closing, whereas the maximum demand

for opening occurs at the instant of opening, for then is the piston moving most rapidly. In my gear in the case of discharge-valves, to which this paragraph chiefly refers, the maximum opening occurs at the instant of 70 opening, the valve being afterward slowly pushed shut in keeping with the diminishing motion of the piston as it nears the end of its stroke. It is further true of other positive valves that the maximum amount of opening 75 available from a given amount of motive mechanism must decrease as the time of opening is delayed. This is much less, and sometimes not at all, true of my valve-gear.

Fourth, preservation of the automatic character of the valve when called upon to open at times when the positive gear connected with it declares it time for being closed and when, with other valves, it would force the valve to be shut. By using an unbalanced 85 valve not rigidly connected to the eccentric it is free to open of itself whenever called upon to do so.

In Fig. 4 I have shown an annular arrangement of ports and valves, 1 representing the 90 stationary cylinder-wall, having ports 5 5 disposed circumferentially around it, and 19 an annular gridiron discharge-valve adapted to oscillate upon the cylinder to open and close 95 said ports. Opposite sides of this valve are 100 connected by links 20 20 with a rock-lever 21, which is oscillated by a rod or stem 22, having connections similar to those of the stem 7. In the case of an admission-valve the valve would be placed on the inside of the cylinder. 100

I claim—

1. In an elastic-fluid compressor, the combination of a compression-cylinder having a grid-valve seat, a grid-valve mounted on said seat, said valve and seat having relatively sliding 105 frictional holding-surfaces adapted to be held together by a difference in the pressures on opposite sides of the valve, positively-moving valve-operating mechanism, and valve-opening resilient means interposed between said mechanism and the valve and brought into opposition to the holding effect of said surfaces by the action of said valve-operating mechanism for permitting a variation in the time of opening the valve. 115

2. In an elastic-fluid compressor, the combination of a compression-cylinder having a grid-valve seat, a grid-valve mounted on said seat, said valve and seat having relatively sliding 120 frictional holding-surfaces adapted to be held together by a difference in the pressures on opposite sides of the valve, positively-moving valve-operating mechanism, a valve-opening spring interposed between said mechanism and the valve, and brought into opposition to the holding effect of said surfaces by the action of said valve-operating mechanism and a dash-pot for cushioning the valve-opening movement produced by said spring. 125

3. In an elastic-fluid compressor, the combi- 130

nation of a compression-cylinder having a grid-valve seat, a grid-valve mounted to slide on said seat and adapted to be held thereto by a difference in the pressures on opposite sides of the valve, positively-moving valve-operating mechanism, a dash-pot having members positively attached respectively to and movable with said mechanism and the valve, and a valve-

opening spring interposed between said mechanism and the valve.

In testimony whereof I have affixed my signature in presence of two witnesses.

SIDNEY A. REEVE.
